CLAIM

The ornamental design for a semiconductor device, as shown and described.

DESCRIPTION

FIG. 1 is a top, left and rear side perspective view of a semiconductor device, showing my new design; FIG. 2 is bottom, right and rear side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is another top, left and rear side perspective view thereof, shown in a used condition mounted on a board shown in broken lines; and,

FIG. 10 is another rear view thereof, shown in a used condition mounted on a board shown in broken lines.

The broken lines shown in the drawing views in FIGS. 9 and 10 form no part of the claimed design.
